UNITED STATES PATENT OFFICE.

FREDERICK HARVEY HUTCHINSON, OF NEW YORK, N. Y.

BOTTLE.

SPECIFICATION forming part of Letters Patent No. 518,606, dated April 24, 1894.

Application filed January 10, 1894. Serial No. 496,445. (No model.)

To all whom it may concern:

Be it known that I, FREDERICK HARVEY HUTCHINSON, of the city, county, and State of New York, have invented a certain new and 5 useful Improvement in Bottles, of which the following is a specification.

My improvement relates particularly to bottles of the kind used in connection with bars and the object is to preclude the dealer from 10 refilling the same with liquor, and thus to enable the purchaser to be certain of obtaining the liquor which was originally put up in any given bottle. It is however applicable to other liquids.

15 My improvement consists in the combination with a bottle or other vessel, of a plug arranged inward of the mouth and provided with a sinuous passage, a valve seat inward of the said plug and a ball valve operating 20 in connection with such seat.

In the accompanying drawings, Figure 1 is a central vertical section of the upper part of a bottle embodying my improvement. Fig. 2 is a similar view illustrating a modification. Fig. 3 includes a plan view, a side view and a bottom view of the plug shown in Fig. 2. Fig. 4 includes a plan view, a side view and a bottom view of a plug of another modified form. Fig. 5 is a side view of a 30 plug of still another modified form. Fig. 6 includes a plan view, a central vertical section, and a bottom view of a plug of another modified form. Fig. 7 is a vertical section of a plug and a portion of a bottle neck, illustrating another modification.

Similar letters of reference designate corresponding parts in all the figures.

A designates a bottle, having a body a, a neck a', and a mouth a''. The inner part of 40 the neck flares outwardly, or in other words, toward the mouth. Near the point where the body joins the neck, is a valve seat a''. With this valve seat is combined a ball valve B which will roll out of place when the bottle 45 is inclined and thus permit of the outward flow of liquid, but will descend to the valve seat when the bottle is raised to a vertical position and thereby prevent the ingress of liquid. Preferably another ball valve B' will be 50 combined with the flaring portion of the neck.

C designates a plug which is intended to be fixed in the neck of the bottle. It may be secured by cement or otherwise. In Fig. 1,

this is shown as having a number of spirally arranged external grooves c, which are open 55 at top and bottom. In Fig. 5, a single spiral groove c' extending circumferentially around a plug is shown. In Figs. 2 and 3 the plug has a vertical groove, c⁵, a circumferential groove c⁶, and a vertical groove c⁹, all of which 60 form one sinuous groove in effect. In these figures I have shown that a spring D, operated substantially like an umbrella catch and arranged within a recess r, in the exterior of the plug may engage with a recess r' 65 in the neck of the bottle to fasten the plug in place. In Fig. 4 I have shown three vertical grooves c¹⁰, c¹¹, c¹², which communicate with a circumferential groove c¹³, the latter being also in communication with three vertical grooves c¹⁴, c¹⁵, c¹⁶. All these grooves 70 form in effect a single sinuous groove. In Fig. 6, I have shown two vertical grooves c¹⁷, c¹⁸, on opposite sides of a plug, and an oblique transverse groove c¹⁹ between the two. 75 These three grooves form in effect a single sinuous groove. In Fig. 7 I have shown the pin c² fitted into a transverse recess c⁸ in the plug. A spring c⁴ is arranged in the recess behind the pin. Opposite the recess the 80 neck of the bottle is provided with a recess into which the pin c² will shoot when the plug is adjusted to its place.

The plug which I employ will prevent the insertion of anything into the neck of the 85 bottle for the purpose of tampering with the valves B or B', and yet it will allow the flow of the liquid outward. The valves will permit the outward flow of the liquid, but will preclude the inward flow. 90

What I claim as my invention, and desire to secure by Letters Patent, is—

The combination with a bottle or other vessel, having an internally flaring neck and a valve seat, of a plug having a sinuous groove 95 and two rolling valves, one coacting with the valve seat and the other with the tapering neck, substantially as specified.

In testimony whereof I have signed my name to this specification in the presence of 100 two subscribing witnesses.

FREDERICK HARVEY HUTCHINSON.
